UNITED STATES PATENT OFFICE.

GEORGE M. FERGUSON, OF ELYRIA, OHIO.

PORTABLE SAFETY-STOP FOR RAILWAYS.

1,142,807.

Specification of Letters Patent. Patented June 15, 1915.

Application filed September 26, 1912. Serial No. 722,482.

To all whom it may concern:

Be it known that I, GEORGE M. FERGUSON, a citizen of the United States, residing at Elyria, in the county of Lorain and State 5 of Ohio, have invented a new and useful Portable Safety-Stop for Railways, of which the following is a specification.

My invention relates to the class of safety devices used in protecting and safeguarding 10 the persons of railway employes when engaged in making repairs to or beneath railway cars positioned on a railway track or switch track.

One object of my invention is to provide 15 a portable safety stop for railway tracks having novel means whereby the apparatus is readily secured or fastened in place at the desired point on the railway track, in position to signal that workmen are engaged in 20 repairing cars on the track beyond the signal and having means for derailing the cars of a train caused to approach the cars being repaired in the event of the target or signal not being observed by the engineer or train- 25 men of the approaching train.

Another object of my invention is to provide 30 a portable safety track target and derailer forming a safety stop having improved means whereby the apparatus is rendered visible either by day or by night.

The invention still further consists in the 35 novel features of construction whereby the apparatus is held and is locked in position on the track, and by which its unauthorized removal is prevented.

Still further objects of the invention will appear as the apparatus is more fully described and claimed hereinafter.

Referring to the accompanying drawings 40 forming part of this specification, Figure 1 is a side elevation of a portable safety stop as constructed and arranged and applied for use to the rail of a railway track, in accordance with my invention. Fig. 2 is an end elevation of the apparatus shown in Fig. 1. Fig. 3 is a detail plan showing the construction of the derailer forming part of my improved apparatus. Fig. 4 is an end elevation of the derailer shown in Fig. 3. Fig. 5 is a sectional end elevation, taken on the line V—V of Fig. 3. Figs. 6 and 7 are similar sectional end elevations, taken respectively on the lines VI—VI and VII—VII of Fig. 3. Fig. 8 is a plan showing a modified form of derailer constructed and arranged and adapted for use in forming my improved safety stop.

In the drawings 2 designates the derailer which is applied for use on the rail 3 of a railway track. In positioning the derailer on the track rail 3 it is placed on the top surface of the rail head with the end 4 of the depending hook flange 5, which is located on one side of the derailer 2, in engagement with the end of one of the splice 60 bars 6 used in connecting the adjoining ends of the rails in the railway track. The depending flange 5 has a hook portion 7 which is arranged to engage with the under side of the head of the track rail 3. The opposite side of the derailer 2 on the end 4 thereof is provided with an overhanging portion 8 having a square opening or hole 9 therethrough in which the T-headed pin or bolt 10 is secured in fastening and locking 70 the derailer 2 in position on the track rail 3 to which it is applied for use. The pin 10 has projecting portions 10^b 11 and 12 on three sides of one end, each of these portions having face portions beveled to fit a different section of track rail.

The shank or upper end of the pin 10 has a groove or slot 13 therethrough in which the taper key 14 is inserted in securing the pin 10 in position on the derailer 2 and the smaller end of the key 14 has an opening 15 therein through which the hook 16 of a padlock 17 extends in locking the derailer to the track rail 3 so as to prevent its being removed or tampered with by persons other than those authorized to remove the derailer, such authorized persons having a key for the padlock 17.

As will be seen by reference to Figs. 3 to 7 the upper face of the derailer 2 is provided with vertically extending ridges or flanges 18 and 19 which extend across the face of the derailer at an oblique angle in such manner as to form a groove which extends transversely across the face of the derailer, this groove being arranged to engage with the flanges 20 on the car wheels A and by such engagement therewith cause derailing of a car which is brought into contact therewith.

In the modified construction shown in Fig. 8 the double derailer 2^a is provided with vertically extending ridges or flanges 18^a and 19^a on each end thereof, the construction of these flanges and the recesses 110 or grooves formed thereby being symmetrical about the lengthwise center of the derailer. At one end of the derailer 2 a vertical post or mast 21 is secured having a

target 22 fastened to its upper end. The target 22 comprises a circular disk having an opening or bull's-eye 23 in the center thereof. The opposite faces of the target 5 are painted red or other striking color and a band 24 of a contrasting color is painted around the outer marginal edge of the disk forming the target 22. A bent arm 25 is fixed to the uppermost edge of the target 22 10 and the upper portion of this arm is provided with a forked end 26 for the purpose of supporting a lantern 27 in such manner that the lantern will be suspended in front of the bull's-eye 23 of the target 22 for use 15 at night or in places which are dark. Transverse holes extend through the lugs forming the slotted or forked end 26 of the arm 25 in which the hook 29 of a padlock 30 is placed in locking the handle of the 20 lantern 27 to the arm or supporting bar 25. Fixed to the post or mast 21 adjacent to the lower edge of the target 22 is a shelf or bracket 31 which extends horizontally and is provided on its marginal edge with a 25 series of vertically extending bent portions 32 forming lugs which engage with the lower edge of the base of the lantern 27 so as to position the lantern in front of the target 22 and prevent its swinging when suspended from the arm 25.

The derailer shown in Fig. 8 is provided with a bent arm 25 and target 22 which are constructed in the same manner as has been before described and the derailer 2^a also is 35 provided with a pin 10 and taper key 14 which is positioned and held on the rail 2 in the same manner as described in connection with the preceding figures.

In using my improved apparatus the derailer 2 is positioned on one of the rails 3 of 40 the track with its end 4 in engagement with the end of a splice bar 6 on the track. The pin 10 is then inserted in the opening 9 in the derailer 2 and the taper key 14 is 45 placed in position in the slot 13 in the end of the pin 10. The hook 16 of a padlock 17 is then placed in the opening 15 in the end of the key 14 and in this manner the derailer 2 is locked in position on the track 50 rail 3. The hook 7 on the depending flange 5 of the derailer together with one of the hooks 10^b 11 or 12 on the pin 10 engage with the under surfaces of the rail head so as to prevent lifting of the derailer 2, while side- 55 wise movement of the derailer on the rail 3 is prevented by the depending flange 5 on one side and the shoulder 10^a of the pin 10 on the opposite side of the rail head, length- 60 wise movement of the derailer on the track rail being prevented in one direction by engagement of the end of the hook 7 on the flange 5 with the end of the splice bar 6.

When it is dark, as at night, the lantern 27 is suspended from the arm 25 so that rays of the light will shine through the bull's-eye 23 and in this way make the target 65 visible in both directions for a considerable distance on each side of the target.

The advantages of my invention will be 70 apparent to those skilled in the art. The apparatus is simple and is easily kept in repair. By the use of my improved portable apparatus a signal or target is easily 75 and quickly placed in position at any point along a railway track to give notice to the trainmen on approaching trains that workmen are engaged in making repairs beyond the target and give warning that the approaching train should stop. The derailer 80 forming a base for the support of the signal will cause approaching trains to leave the track in cases where the signal or target is not observed by the engineer or the trainmen of the approaching train, and in this way liability of collisions with the cars being 85 repaired and injury to the workmen engaged in making such repairs is prevented and overcome.

With the construction shown in Fig. 8 90 the derailer can be positioned at any point on a railway track so that a stop signal will be given by the target or, in case the signal is not observed, the cars will be derailed by engagement with the derailer when going in either of opposite directions.

Modifications in the details of the construction of the parts may be made without departing from my invention as defined in the appended claims.

I claim:

1. The combination with a derailer having a rail head engaging flange on one side, a slotted lug on the other side, a securing member passing through the lug and adapted to engage beneath a rail head opposite 105 the flange, and a lock for holding the securing member in position.

2. The combination with a derailer having a rail head engaging flange on one side, a slotted lug on the other side, a securing member, having a transverse slot passing through the lug and adapted to engage beneath a rail head opposite the flange, and a locking device comprising a wedge adapted 110 to pass through the transverse slot and having a padlock shackle receiving opening in its smaller end for holding the securing member in position.

In witness whereof, I have hereunto set my hand.

GEORGE M. FERGUSON.
